DESIGN FOR A REGISTER PLATE FOR A GAME APPARATUS

Herbert G. Breitenstein, Chicago, Ill., assignor to Raymond T. Moloney, Chicago, Ill.

Application February 28, 1934, Serial No. 50,906

Term of patent 3½ years

To all whom it may concern:

Be it known, that I, HERBERT G. BREITENSTEIN, a citizen of the United States, residing at Chicago, in the county of Cook and State of Illinois, have invented a new, original, and ornamental Design for a Register Plate for a Game Apparatus, of which the following is a specification, reference being had to the accompanying sheet of drawing, forming part thereof.

I claim:

The ornamental design for a register plate for a game apparatus, as shown.

HERBERT G. BREITENSTEIN.
